UNITED STATES PATENT OFFICE.

JOHN W. CULMER, OF NEW BRIGHITON, PENNSYLVANIA.

DESIGN FOR A FRAME FOR WEIGHING-SCALES.

SPECIFICATION forming part of Design No. 24,951, dated December 3, 1895.

Application filed July 29, 1895. Serial No. 557,506. Term of patent 3½ years.

To all whom it may concern:

Be it known that I, JOHN W. CULMER, a citizen of the United States, residing at New Brighton, in the county of Beaver and State of Pennsylvania, have invented and produced a new and original Design for a Frame for Weighing-Scales; and I do hereby declare the following to be a full, clear, and exact description of the same, reference being had

o to the accompanying drawing, forming a part thereof.

The leading feature of this design consists in the external and ornamental shape and appearance given to a frame within which is to be contained the mechanism of a weighing-scale.

In the drawing, A is the base of the design; B, the seat of the frame; C, the standard part of the frame at the rear of base and

seat, and D a thin narrow bar rising vertically from the left-hand end of the standard, 20 then curving horizontally and extending beyond the right-hand end of the standard, seat, and base, then curving vertically downward, and then horizontally inward to a union with the standard at its right-hand end, all as 25 shown in the drawing.

I claim—

The design for a scale frame, substantially as herein shown and described.

In testimony whereof I affix my signature 30 in presence of two witnesses.

JOHN W. CULMER.
